UNITED STATES PATENT OFFICE

PETER GRAHAM MACGREGOR, OF PEQUANOCK, NEW JERSEY, ASSIGNOR TO PYRENE MANUFACTURING COMPANY, OF NEWARK, NEW JERSEY, A CORPORATION OF DELAWARE

FIRE EXTINGUISHER

Application filed January 18, 1929. Serial No. 333,416.

This invention relates to fire extinguishers of the pressure type characterized by a container for the fire extinguishing liquid and a cartridge containing a highly compressed gas such as carbon dioxide which, when the cartridge is punctured, produces within the container a pressure which expels the fire extinguishing liquid therefrom. The structure hereinafter described in which the invention is embodied is particularly adapted for use with a highly volatile fire extinguishing fluid such as methyl-bromide, although it is not limited to use in that connection.

The general object of the invention is to provide a new and improved fire extinguisher of the type above mentioned which is simple in construction, reliable and efficient in operation, is easily recharged after use, and may be readily inspected to make sure that it is in proper working order.

Besides certain highly advantageous features of construction and combination of parts, the invention is characterized by the facts that the chamber or receptacle containing the fire extinguishing fluid is normally tightly sealed by a sealing means such as a puncturable diaphragm which prevents the fire extinguishing fluid from escaping through the outlet passage, and the gas-containing cartridge is located outside this sealed chamber so that it may be easily removed at any time for inspection and renewal. Other novel features of the invention will be apparent from the following description of the embodiment thereof illustrated in the accompanying drawing in which Figure 1 is a central, longitudinal, sectional view of an extinguisher embodying the invention, certain parts thereof being broken away intermediate the ends of the extinguisher; Figure 2 is a horizontal, sectional view taken on the line 2-2 of Figure 1; Figure 3 is an enlarged horizontal sectional view taken through the valve mechanism on line 3-3 of Figure 1; and Figure 4 is a longitudinal sectional view of the cartridge holding and puncturing mechanism showing the seal broken and the cartridge as having been moved into cartridge-piercing position.

60 The fire extinguisher includes a shell 10

which serves as a container for a suitable fire extinguishing medium, such as methyl-bromide. To one end of the shell 10 is connected, as by brazing or soldering, a head 11, provided with a filling opening through 55 which the container may be filled with fire extinguishing liquid, and into which a sealed cartridge 12, carrying a compressed gas such as carbon-dioxide, may be inserted and there held ready for use when the extinguisher is 60 operated in the manner hereinafter more particularly described.

The closure for the filling opening of the container 10 includes an internally screw threaded bushing 13, connected at its upper 65 end by brazing or soldering, to the head 11. The closure also includes an externally screw threaded head or housing 14, having a chamber 15 adapted for the reception of the cartridge 12. This housing 14 is formed at one 70 end with an opening 17, adapted for the reception of a striking pin or plunger 18 adapted to cooperate with the cartridge 12 to move the same when it is desired to release its contents in a manner hereinafter described. The 75 striking plunger 18 is limited in its longitudinal movements by a shoulder 19 carried thereby and adapted to engage the bottom wall of the pocket within which the shoulder is carried and also adapted to engage a washer 80 21 seated in an internally screw threaded opening at one end of the housing 14, within which opening is carried a screw threaded gland nut 22 adapted to cooperate with the washer 21 for holding a suitable packing material 23 in position about the striking pin 18. Preferably, the outer end of the striking pin 18 is provided with a suitable head or button 24 to which a blow may be delivered for actuating the striking pin to release the contents of the cartridge 12.

The bushing 13 is formed with a seal receiving ledge 25, having an annular groove 26 therein and adapted for the reception of a suitable metallic disc or seal 27, preferably 95 of thin sheet metal, which serves to normally prevent the liquid contents of the fire extinguisher from entering the discharge tube hereinafter more particularly described. This sealing disc 27 is retained in position 100

upon the ledge 25 by an annular clamp ring 28, having an annular bead 29 which is adapted to engage the outer margin of the sealing disc 27 and force the same into the groove 26 to provide an adequate sealing engagement of the sealing disc with the ledge 25. The annular ring 28 is formed on its periphery with a shoulder 30, with which an annular flange 31 carried by the housing 14 is adapted to engage so that the ring 28 may be forced down firmly into sealing engagement with the disc 27 as the head 14 is screwed into the bushing 13, the ring 28 being provided with a flange or skirt 32 adapted to fit within the annular flange 31.

The bushing 13 is provided at its inner end with a cage-like extension 35 having a plurality of openings 36 through which the contents of the cartridge 12 passes into the container 10 when the cartridge is punctured and through which the liquid contents of the extinguisher passes as it is being expelled, in a manner hereinafter described. The end portion of the extension 35 carries a cartridge puncturing pin 37 which is suitably attached to the bottom of the extension 35, the pointed end of such pin being located in proximity to the sealing disc 27 and in axial alignment with the cartridge 12. Surrounding and engaged by the neck portion of the cartridge 12 is a seal fracturing device in the form of a tubular cutter 38 having a flared cutting portion 40 which has a sliding fit within the bore of the cage-like extension 35.

As the cartridge 12 is moved longitudinally and inwardly by the thrust of the striking pin 18, the tubular cutter 38 cuts out the entire central area of the sealing disc 27 by a shearing action, and the inward movement of the cartridge 12 causes the striking pin 18 to pierce the cut-out portion of the sealing disc 27 and puncture the end of the cartridge, thereby releasing its contents which escapes into the container 10 through the openings 36 in the cage 35. This cutting out of the central portion of the sealing disc 27 and its movement inwardly also permits the fire extinguishing liquid to pass through the openings 36 in the extension 35 into the annular space 41 between the cutter 38 and the inner wall of the ring 28. Leading from this annular space 41 are a plurality of radial passages 42 through the wall of the ring 28 which communicate with a peripheral groove 43 formed in the outer surface of the ring 28. The annular space formed between the wall of the groove 43 and the inner wall of the bushing 13 is in communication through an outlet passage 44, formed in the bushing 13, with a discharge tube 45, as clearly shown in Figure 1. The discharge tube 45 communicates with the valve chamber 46 formed in a valve housing 48 located within the receptacle 10 and having its outer end projecting through the wall of that receptacle and

suitably connected to the same by a liquid tight joint.

Slidable within the housing 48 is a valve stem 49, carrying at its outer end a suitable head or button 50 and provided at its other end with an internally screw threaded socket 51 and an external shoulder 52. Upon the valve stem 49 is carried a cone shaped valve 53, the smaller end of which engages the shoulder 52 and the larger end of which is engaged by a disc 54 carried by a guide pin 55, one end of which is screwed into the socket 51 of the valve stem 49 and the other end of which is slidably within a socket 56, formed in an extension or boss 57, carried by a closure plate 58 for the chamber 46, the plate 58 being suitably connected to the housing 48. Normally the valve 53 is maintained seated upon its seat by a compression spring 59, carried within the chamber 46, one end of such spring being in engagement with the disc 54 and the other end thereof being in engagement with the closure 58. When it is desired to establish communication between the chamber 46 and an outlet chamber 60 formed in the housing 48, the valve 53 is moved out of engagement with its seat by depressing the valve stem against the compression spring 59. From the chamber 60 leads a discharge pipe 62, which extends through the end wall of the receptacle 10 and is there suitably connected to a discharge nozzle 63, the base portion of which is seated within a cup-shaped depression 64, formed in the end wall of the receptacle and suitably connected thereto, as by brazing or soldering. Preferably, the screw threaded end of the discharge pipe 62 is provided with a gland nut 65, between which and the discharge nozzle 63 is confined a suitable packing 66, which surrounds the screw threaded end of the discharge tube 62 and is located within the relatively large opening through which the discharge pipe 62 passes.

To operate the extinguisher, it is held with its discharge nozzle 63 pointed generally upwardly as shown in Figure 1, whereupon the striking plunger 18 is subjected to a blow, thereby causing it to move longitudinally within the housing 41. As the striking plunger so moves, the cartridge 12 is moved along its longitudinal axis carrying with it the cutter 38 which serves to blank or cut out the central area of the sealing disc 27. Upon continued movement of the cartridge 12, the pointed end of the piercing pin 37 punctures the end of the cartridge with the result that its contents escape through the openings 36 of the cage-like extension 35 and create a pressure over the liquid contents of the extinguisher, which pressure may be utilized to expel the fire extinguishing medium. After releasing the contents of the cartridge 12, the fire extinguishing liquid is permitted to escape through the openings 36

of the cage-like extension 35, into the chamber 41 about the reduced intermediate portion of the cutter 38, through the radial passages 42 into the discharge pipe 45 leading to the valve chamber 46. By depressing the valve stem 49 to open the valve 53 between the chambers 46 and 60 with which the discharge pipes 45 and 62 communicate, respectively, the liquid may be permitted to pass through the pipe 62 to the nozzle 63. Not only does the valve 53 serve to release the fire extinguishing liquid from the receptacle 10, but it also enables such of the fire extinguishing medium as may remain within the receptacle 10 upon the extinguishing of a conflagration to be retained.

In order to refill the extinguisher for use, the housing 14 is removed and the clamp ring 29 is withdrawn thereby permitting the punctured seal 27 to be removed. With the housing 14, sealing ring 28 and the punctured seal 27 removed, the extinguisher may be refilled with a suitable fire extinguishing liquid, whereupon a new seal is introduced 25 and clamped in place by the ring 28 which is forced down into intimate engagement with the peripheral margin by screwing the housing 14 into position, it being understood that a new sealed cartridge 12 carrying a 30 compressed gas is substituted for the punctured cartridge before the housing 14 is applied and that the circular cutter 38 is placed in position about the new cartridge to remove the central area of the sealing disc when the 35 extinguisher is next operated.

While only one form of the invention is herein shown and described, it will be understood that various changes may be made without departing from the spirit of the invention or the scope of the following claims.

What is claimed is:

1. A fire extinguisher comprising a liquid receptacle having an outlet, a seal normally closing said outlet, a sealed cartridge containing a compressed gas to be released and directed into said receptacle, a seal fracturing device in cooperative relation to said seal, and cartridge puncturing means separate from seal-fracturing means and rendered effective upon operation of said seal fracturing device to release the contents of said cartridge.

2. A fire extinguisher comprising a liquid receptacle having an outlet, a seal normally closing said outlet, a sealed cartridge containing compressed gas to be released and directed into said receptacle, means for movably supporting said cartridge, actuating means for moving said cartridge, a seal fracturing device movable with said cartridge, and cartridge puncturing means with reference to which said cartridge is movable to render such means effective in puncturing said cartridge.

3. A fire extinguisher comprising a liquid

receptacle having an outlet, a seal normally closing said outlet, a sealed cartridge containing a compressed gas to be released and directed into said receptacle, a seal fracturing device located on one side of said seal and in cooperative relation to said seal, and cartridge puncturing means located on the other side of said seal and rendered effective upon operation of said seal fracturing device to release the contents of said cartridge.

4. A fire extinguisher comprising a liquid receptacle having a compartment for carrying a fire extinguishing medium and having an outlet adapted to communicate with said compartment, a seal normally closing communication between said compartment and said outlet, a sealed cartridge located without said compartment and containing compressed gas to be released and directed into said compartment, a seal fracturing device for opening communication between said compartment and said outlet, and cartridge puncturing means separate from said seal-fracturing means and rendered effective upon operation of said seal fracturing device to release the contents of said cartridge.

5. A fire extinguisher comprising a liquid receptacle having an outlet, a seal normally preventing the passage of liquid from said receptacle to said outlet, a sealed cartridge containing a compressed gas movably supported outside said seal, a seal fracturing device movable with said cartridge, cartridge puncturing means supported within said receptacle on the inside of said seal, and means for moving said cartridge and seal fracturing device to effect the fracturing of the seal and the puncturing of said cartridge.

6. A fire extinguisher comprising a liquid receptacle having a compartment for carrying a fire extinguishing medium and having an outlet adapted to communicate with said compartment, a seal normally closing communication between said compartment and said outlet, a sealed cartridge located without said compartment and containing compressed gas to be released and directed into said compartment, a seal fracturing device associated with said cartridge, means for moving said cartridge and for simultaneously moving said seal fracturing device to open communication between said compartment and said outlet through said seal, and cartridge puncturing means with reference to which said cartridge is displaceable to render the same effective in puncturing said cartridge.

7. A fire extinguisher comprising a liquid receptacle having a compartment for carrying a fire extinguishing medium and having an outlet adapted to communicate with said compartment, a housing associated with said receptacle, a sealed cartridge movably mounted within said housing and without said compartment and containing a compressed gas to be released and directed into said compartment.

ment, a seal normally closing communication between said compartment and said outlet, a seal fracturing device associated with said cartridge and movable therewith, a longitudinally movable striking pin slidable within said housing for moving said cartridge and for simultaneously moving said seal fracturing device to open communication between said compartment and said outlet through said seal, and cartridge puncturing means with reference to which said cartridge is movable to render the same effective in puncturing said cartridge.

8. A fire extinguisher comprising a liquid receptacle having an outlet and a filling opening, a closure for said filling opening including a bushing having a ledge, a seal peripherally supported upon said ledge, a clamp ring engaging the peripheral margin of said seal, a housing associated with said bushing and engaging said clamp ring, a longitudinal movable sealed cartridge carried within said housing and containing a compressed gas to be released and directed into said receptacle, a seal fracturing device for opening communication between said receptacle and said outlet, a cartridge puncturing means rendered effective upon operation of said seal fracturing device with reference to which said cartridge is movable to render the same effective in puncturing said cartridge.

9. A fire extinguisher comprising a liquid receptacle having an outlet and a filling opening, a closure for said filling opening including a bushing having a ledge, a seal peripherally supported upon said ledge, a clamp ring engaging the peripheral margin of said seal, a housing associated with said bushing and engaging said clamp ring, a longitudinal movable sealed cartridge carried within said housing and containing a compressed gas to be released and directed into said receptacle, a seal fracturing device for opening communication between said receptacle and said outlet, a cartridge puncturing means rendered effective upon operation of said seal fracturing device with reference to which said cartridge is movable to render the same effective in puncturing said cartridge, and a valve for controlling the escape of fire extinguishing liquid to said outlet.

In testimony whereof, I have affixed my signature to this specification.

PETER GRAHAM MacGREGOR.
